UNITED STATES PATENT OFFICE.

OSCAR ANDERSON, JR., AND THOMAS McCARTHY, OF FALL RIVER, MASSACHUSETTS.

BOTTLE WASHER.

Application filed October 15, 1923. Serial No. 668,671.

To all whom it may concern:

Be it known that we, OSCAR ANDERSON, Jr., and THOMAS McCARTHY, citizens of the United States, residing at Fall River, in 5 the county of Bristol and State of Massachusetts, have invented certain new and useful Improvements in Bottle Washers; and we do declare the following to be a full, clear, and exact description of the invention, such as will enable others skilled in the art to which it appertains to make and use the same.

Our invention relates to improvements in bottle washers of the type in which a washing brush is carried and operated by a shaft, one object being to produce a unique means, in the form of a cylinder through which the shaft passes, for guiding the brush into the bottle to be cleaned, and for receiving the brush as it is withdrawn from the bottle, thus preventing any of the washing liquid from being spattered onto the operator, by the brush, both when washing the bottle and when withdrawing the brush through the 25 bottle neck.

Another object is to provide a cylinder of the type set forth, which may be engaged either with a milk bottle, or with the neck of another form of bottle, such as a beverage 30 bottle or a nursing bottle.

In the preferred construction, reciprocation of the shaft through the cylinder, produces rotation of said shaft, and a further aim is to provide novel bearing means for the shaft preventing binding thereof on the walls of the guides through which it passes.

Yet another object is to make improved provision for connecting the brush to the shaft, in such a manner as to give free movement to said brush within the bottle being cleaned.

It is another object of the invention to provide a bottle cleaning device which will be simple and inexpensive, yet will be efficient and desirable, and extremely easy to operate.

With the foregoing in view, the invention resides in the novel subject matter herein-after described and claimed, the description being supplemented by the accompanying drawings.

Figure 1 is a side elevation showing one form of the washer engaged with a milk bottle.

Figure 2 is a vertical sectional view showing the device on the neck of another form of bottle.

Figures 3 and 4 are transverse sectional views on lines 3—3 and 4—4 of Fig. 2.

Figure 5 is an enlarged longitudinal section showing the manner of attaching the brush to the shaft.

Figure 6 is a detail transverse section on line 6—6 of Fig. 5.

Figure 7 is a longitudinal sectional view of a modified form of construction.

Figure 8 is a view similar to Fig. 7 but showing a still further form of construction.

Figure 9 is an enlarged longitudinal sectional view through the handle and its bearings.

In the drawings above briefly described, the numeral 1 designates a straight shaft formed by twisting two lengths of stiff wire 2, together, the lower end of said shaft being provided with a bottle cleaning brush 3, while the upper end of said shaft is equipped with a suitable handle 4. In connecting the brush 3 with the shaft 1, we make use of a metal sleeve 5 into whose upper end, the lower ends of the wires 2 extend, said upper end of the sleeve being flattened upon said wires and bent inwardly between same as indicated at 6, so as to effectively hold the sleeve upon the shaft. 80

The brush 3 is preferably provided with a twisted wire shank 7 having an attaching eye 8 at its upper end which is received loosely in the lower end of the sleeve 5, a screw or pin 9 being passed across said sleeve and through the eye. By this construction, the brush is connected with the shaft for free movement in a bottle being washed so that all parts of the latter may be reached, and it will be seen that by removing the screw 9, the brush may be detached if desired.

The preferred manner of connecting the handle with the shaft 1, is shown most particularly in Fig. 9. A metal sleeve 10 is soldered or otherwise secured around the upper end of the shaft, said sleeve being provided near its upper end with an outstanding bearing flange 11. This flange portion of the sleeve is received in an internal recess 12 in the handle 4, and opposite sides of said recess are provided with ball races 13, between which and the flange 11, bearing balls

14 are positioned. Thus, an anti-friction connection is established between the handle and shaft which permits free rotation of the latter within said handle. This handle 5 is preferably of the two-part construction disclosed in Fig. 9 with the two sections connected in any suitable manner as indicated at 15.

We provide a light-weight cylinder 16 10 through which the shaft 1 passes, said cylinder being formed of wood, aluminum, or any other desired material. The upper end of this cylinder is closed by a head 17 through which the shaft 1 passes, while the 15 lower end of this cylinder is open. This lower end, as shown most clearly in Figs. 1 and 2, is preferably of such external diameter as to be receivable snugly in the mouth of a milk bottle B and such internal diameter 20 as to be applicable about the neck of a smaller bottle B', for instance a nursing bottle. To limit the insertion of the bottle neck into the cylinder 16, the latter is provided with an internal stop shoulder 18 25 and this shoulder is preferably flared downwardly to accommodate bottle necks of slightly varying sizes.

If desired, instead of using the stop shoulder 18, a split wire ring 18^a may be engaged 30 with an internal groove 18^b in the lower portion of the cylinder 16, as shown in Fig. 7. This construction is used principally when the device is employed for cleaning beverage bottles.

Snugly held in a suitable socket or recess 19, in the head 17, is a metal bearing cylinder 20 whose end walls 21 have openings 22 through which the shaft 1 passes, diametrically opposite points of the walls of said 40 openings, being provided with projections 23 receivable in the diametrically opposed ways which are formed in the shaft 1, by its twisted wire formation. It will thus be seen that when the shaft is reciprocated 45 through the cylinder 16, the slowly pitched ways of said shaft and the projections 23, will coat, in rotating said shaft. To prevent binding of the shaft against the walls of the openings 22, by accurately centering 50 said shaft in the bearing cylinder 20, we fill the portion of the shaft ways within the cylinder 20, with two rows of bearing balls 24, each row being equal in length to the internal length of said cylinder 20. All of 55 the balls 24 engage the wall of the cylinder 20 and thus the shaft 1 is accurately centered in the latter and it will not whip or bind excessively upon the walls of the openings 22, thereby producing a device which will 60 operate with extreme ease.

In the form of construction shown in Figs. 1 and 2, the cylinder 20 is held in the recess 19 by a cap plate 25 secured to the head 17 by countersunk screws 26. In the construc-

tion illustrated in Fig. 7, the head 17 is provided with an upper section 25^a separate from its lower portion and secured thereto in any desired manner, the two sections of the head being jointly recessed to provide the socket or the like 19. In Fig. 8, the cylinder 20 is held in place by a cap plate 25^b seated in a countersink 27 in the upper end of the head 17, the edge wall of the countersink being preferably turned slightly as indicated at 28, to secure the plate 25^b in place.

If desired, any form of the device may be provided with an inlet valve 29 connected with a suitable pipe or hose 30 for conducting water or any other washing liquid to the interior of the cylinder 16 and consequently supplying such liquid to the bottle being washed. This construction is shown only in Fig. 8.

To apply the device to a bottle, the shaft 1 is moved upwardly through the cylinder 16 to position the brush 3 in the latter. Then, the lower end of said cylinder is engaged with the bottle to be cleaned and the shaft is forced downwardly, thus moving the brush 90 into the bottle, the latter having been previously filled to a suitable extent with a cleaning liquid, unless the valve 29 and hose 30 are used. When these parts are employed, the cleaning liquid is not supplied to the bottle until the cylinder 16 is engaged with the latter. Reciprocation of the shaft 1, by means of the handle 4, will now cause both reciprocation and rotation of the brush 3 to thoroughly wash the bottle. Before the device is removed from the bottle's neck, the brush 3 is drawn into the cylinder 16. This is greatly advantageous over ordinary forms of bottle washers, in which the brush bristles throw the washing liquid upon the operator 95 as they snap out of the bottle neck.

The device is simple and inexpensive, yet is efficient and desirable and may be operated very easily.

As excellent results may be obtained from the details disclosed, these details may well be followed, but within the scope of the invention as claimed, numerous minor changes may be made.

We claim:

1. A bottle cleaner comprising a body formed with a central socket, a bearing cylinder secured in said socket and having end walls formed with aligned openings, a shaft passing through said openings and having slowly pitched helical ways, said body having portions received in said ways to produce rotary motion of the shaft when the latter is reciprocated, and rows of bearing balls in the portions of said ways within said bearing cylinder, said balls engaging the cylinder wall.
2. A device of the class described compris-

ing a shaft and a hollow cylinder having openings in its end walls through which said shaft passes, said cylinder and shaft being relatively reciprocable and the latter 5 being formed with slowly pitched ways, said cylinder having portions received in said ways to produce rotation of the shaft, and

rows of bearing balls in the portions of said ways within the cylinder, said balls engaging the wall of said cylinder.

In testimony whereof we have hereunto affixed our signatures.

OSCAR ANDERSON, JR.
THOMAS McCARTHY.
